TUYÈRE FOR SHAFT FURNACES

Julius Stoecker, Bochum, Germany, assignor to
Vereinigte Stahlwerke Aktiengesellschaft, Dus-
seldorf, Germany

Application July 3, 1933, Serial No. 678,954
In Germany July 7, 1932

1 Claim. (Cl. 266—41)

This invention relates to a tuyère for shaft furnaces.

It is known to employ for the regulation of the nozzle section in the blast pipes of shaft furnaces 5 rotatable nozzles which, for this purpose, have an oval or star-shaped outlet opening. It is further known to use nozzles having an orifice displaced relative to the longitudinal axis.

The invention proposes a tuyère for shaft furnaces, in which the opening of the nozzle is displaced relative to the longitudinal axis and the direction of the blast can be varied owing to the fact that the nozzle is rotatable about its axis.

The advantages afforded by the invention are 15 that during prolonged stopping of furnaces due to reductions in output obstructions which are frequently formed to the left and right of the tuyère as well as above it and which have to be removed by melting to insure satisfactory operation 20 of the tuyères can be eliminated by melting by means of the new tuyère according to requirements.

Furthermore, in order to prevent the breaking out of tap holes, especially in case of larger outputs, it is necessary to plug one or sometimes two 25 of the tuyères disposed laterally to the tap hole, which has an unfavorable effect upon the working of the furnace. The invention makes it pos-

sible to deflect the blast from the tap hole by turning the tuyères to the right or left and thus to protect it against damage. Moreover, merely by turning the tuyère 180° and thus deflecting the blast upwardly narrowing of the bosh is eliminated.

By way of example, the invention is illustrated in the accompanying drawing, in which Figures 1, 2 and 3 are views of different embodiments of the invention.

Referring to Figs. 1 and 2, 1 is a tuyère of standard type which in its upper half possesses a wedge-like insertion 2 capable of being covered by the cooling water of the tuyère.

In the constructional form shown in Fig. 3 the 15 lower inner nozzle plate 3 is bent so as to impart to the tuyère a form resembling an elbow part.

I claim:—

A tuyère for shaft furnaces, especially blast furnaces, consisting substantially of a double-walled nozzle the center of the opening of which is displaced relative to the longitudinal axis of the nozzle while the nozzle itself is rotatable about its axis so that the blast direction may be varied, the inner wall of the nozzle projecting 20 inwardly at the opening in a wedge-like shape. 25

JULIUS STOECKER.
